UNITED STATES PATENT OFFICE.

CLAYTON E. FREDERICKSON, OF BERKELEY, CALIFORNIA.

FOUR-CYCLE INTERNAL-COMBUSTION ENGINE.

1,172,976.

Specification of Letters Patent. Patented Feb. 22, 1916.

Application filed April 10, 1913, Serial No. 760,233. Renewed January 8, 1916. Serial No. 71,135.

To all whom it may concern:

Be it known that I, CLAYTON E. FREDERICKSON, residing at Berkeley, in the county of Alameda and State of California, have invented certain new and useful Improvements in Four-Cycle Internal-Combustion Engines, of which the following is a specification.

Primarily the invention has for its object to provide an engine of the four cycle type employing hollow sleeve or piston valves for controlling the intake and exhaust ports of the working cylinder, the valves being so designed that the charges pass through the interior of the valves intermediate the ends of the same so as to not over heat the packing rings which are employed, thus lengthening the life of the valves and adding to the efficiency of operation of the engine.

The invention further includes those novel details of construction, combination and arrangement of parts, all of which will be first fully described, then be specifically pointed out in the appended claim, reference being had to the accompanying drawings, in which:

Figure 1 is a vertical section taken through the valves and working cylinder. Fig. 2 is a detail horizontal section on the line 2—2 of Fig. 1. Fig. 3 is a detail perspective view, parts being broken away, of the upper end of the piston. Fig. 4 is a view similar to Fig. 3 showing a modification of the same. Fig. 5 is a detail perspective view, with parts broken away of the inlet valve shown in Fig. 1. Fig. 6 is a view similar to Fig. 1 of a modification of the invention showing the same adapted to an engine of the single piston type.

In the drawings, 1 is the crank case on which the engine cylinder 2 (or cylinders when more than a single cylinder is employed) is fastened. The cylinder 2 is in communication with the crank case and with the valve casings 3 and 4, that inclose the intake and exhaust valves respectively. The valve cases 3 and 4 may be cast integrally with the main cylinder 2, if desired.

In the preferred embodiment of the invention, as a double piston type, the cylinder 2 is of two diameters to inclose two working chambers 5 and 6, in which the piston 7 operates. The piston 7 is of the

"hat" type having two piston heads or pressure areas 8 and 9. The piston 7 is provided with two sets of packing rings 10 and 11 near its upper end between which rings the piston is separated, as at 12, to form an annular groove, as it were, whereby any leakage past the packing rings 10 will be conveyed directly into the piston 7 and consequently into the crank case from which the leakage gases may be bled in any desired way.

The piston 7, when the groove 12 is formed by a complete separation of the piston shell, is strengthened and braced by bridging lugs 13 but where the groove 12* does not pass entirely through the piston shell, such lugs may be omitted, if desired (see Fig. 4), and in the event of this construction, a set of bores or ports 16 effect communication between the groove 12* and the interior of the piston.

The provision of the grooves 12 or 12* in relatively free communication with the interior of the piston and crank case, enables the lubricant in the crank case to be splashed into the groove, thereby lubricating the cylinder and piston walls in a very effective manner.

The cylinder 2 has an inlet port 17 or 17* for the working chamber and a corresponding exhaust port 18 or 18* for the same.

The inlet port 17 or 17* is adapted to communicate with the new charge supply port 19, in the valve case 3, through the controlling influence of the inlet valve 20. The inlet valve 20 is preferably hollowed or chamfered out as at 21 or 21* to effect a free passage between the intake port 22 or 22* and the valve discharge port 23 or 23* respectively, the ends of the valve 20 being packed with one or more rings 24 to prevent leakage in those directions, while intermediate rings 25 prevent leakage from one section of the valve to the other.

The provision of the end rings in the valves 20 and 26 at places beyond the ports, which places are never brought into alignment with the working cylinder ports, is particularly advantageous in the exhaust valve structure, since the hot gases will be unable to sufficiently heat the packing rings 10 to cause them to lose temper or be carbonized and cause them to become ineffective. The exhaust valve 26 has end rings 27—28 (in-

termediate rings being dispensed with if desired) and it has the ports 29—29^x to conduct the exhaust gases into the valve chamber from which the gases escape through the outlet valve port 30 into the exhaust pipe 31.

The cylinder 2 is suitably water jacketed around the working chambers, or such chambers may be cooled in any other desired way.

Any desired ignition system may be employed in the engine and the valves may be operated from the crank shaft in any desired fashion, although I prefer to provide valve crank shafts 32, gear driven from the main crank shaft 33 and connected with the valves by connecting rods 34. The connecting rod 35 connects the piston 7—8 with the crank shaft 33.

In operation the charge is alternately ignited in the two working chambers so that there may be a working impulse on each down stroke of the piston, when the double piston arrangement of Fig. 1 is employed. When the single piston arrangement of Fig. 6 is employed an explosion occurs at every other down stroke of the piston in the usual manner.

From the foregoing description, taken in connection with the accompanying drawing, it is thought the complete construction, operation and advantages of the invention will be apparent to those skilled in the art.

What I claim is:—

In an internal combustion engine, a cylinder and piston, a crank shaft and a connecting rod between said crank shaft and piston, said cylinder having inlet and outlet ports, an inlet and an exhaust valve cylinder in communication with the respective ports, hollow valves of the piston type operating in said valve cylinders, co-operative timed connections between said valves, and the crank shaft, said valves having packing rings adjacent each end, said exhaust valve cylinder having an exhaust port and said inlet valve cylinder having an inlet port, said valves having ports intermediate the end packing rings for registering with the respective ports of said valve cylinders and said piston cylinder, said valve operating connections including means for moving said valves to bring said ports into and out of register, and maintain said packing rings always out of register with the respective working cylinder ports whereby heated gases will be kept out of contact with the packing rings of the valves, the inlet and exhaust ports of the valves being staggered with relation to each other, substantially as shown and described.

CLAYTON E. FREDERICKSON.
